SURGICAL SCRUB TRAY

Martin Link, North Brunswick, N.J., assignor to
Johnson & Johnson

Filed July 29, 1971, Ser. No. 167,544

Term of patent 14 years

Int. Cl. D24—02; D9—03

U.S. Cl. D83—1 U

FIG. 1 is a top view of a surgical scrub tray showing my new design.

FIG. 2 is a side view thereof, the opposite side being identical.

FIG. 3 is an end view, the opposite end being identical.

FIG. 4 is a cross sectional view along the lines 4-4 of FIG. 1.

FIG. 5 is an enlarged cross sectional view along the lines 5-5 of FIG. 1.

FIG. 6 is an enlarged cross sectional view along the lines 6-6 of FIG. 1.

FIG. 7 is an enlarged cross sectional view along the lines 7-7 of FIG. 1.

I claim:

The ornamental design for a surgical scrub tray, substantially as shown.
